UNITED STATES PATENT OFFICE

171,823

SERVING STAND

Humphrey F. Parker, Buffalo, N. Y.

Application June 29, 1953, Serial No. 25,707

Term of patent 14 years

(Cl. D85—2)

To all whom it may concern:

Be it known that I, Humphrey F. Parker, a citizen of the United States, residing at 81 Humboldt Parkway, Buffalo 14, county of Erie, State of New York, have invented a new, original, and ornamental Design for Serving Stand, of which the following is a specification, reference being had to the accompanying drawing, forming part thereof.

Fig. 1 is a perspective view of a serving stand, showing my design;

Fig. 2 is a front elevation of the stand as shown in Fig. 1;

Fig. 3 is a top plan view of the stand; and

Fig. 4 is a cross-sectional view thereof taken on the line 4—4 of Fig. 2.

The drawing figures are stippled to indicate color contrast, and portions thereof are lined to indicate transparency. This application is a continuation-in-part of my application, Serial No. D. 15,930, filed July 18, 1951, now abandoned.

I claim:

The ornamental design for a serving stand, as shown and described.

HUMPHREY F. PARKER.
